MANUFACTURE OF RECTANGULAR RESTRICTED OPENING SHEET METAL RECEPTACLES

John H. Gonda, Salem, Ohio, assignor to Mullins Manufacturing Corporation, Salem, Ohio, a corporation of New York

Application February 13, 1941, Serial No. 378,751

8 Claims. (Cl. 113—120)

The invention relates to the stamping, drawing, and working of sheet metal articles such as sheet metal receptacles. More particularly, the invention relates to a method of forming a generally rectangular or square, relatively deep container or receptacle, preferably having rounded corners at the corners of the rectangle or square and having integral bottom, side and rounded corner walls terminating in an integral, preferably rounded inturned flange forming a restricted opening at the upper or open end of the side and corner walls, by stamping, drawing, shaping and treating operations from a single piece or blank of sheet or plate metal; and furthermore, the invention relates to the described one-piece sheet metal products.

Such receptacles may be used for many purposes, and particularly as tubs for power driven washing machines. Restricted opening square tubs for washing machines have been particularly desired by certain users. Heretofore, such tubs have been made of aluminum cast in one piece free from any seams or welds or cutting or slitting; and the cost of the same has been materially in excess of the cost of a similar article if it could be formed of sheet steel.

However, it has always been believed that it would be impossible to make a rectangular or square restricted opening tub with an integral bottom wall from a single piece or blank or sheet metal free of slitting, cutting, notching, seams or welds.

Difficult drawing operations are involved in the manufacture of such receptacles, per se, because the same are relatively deep, and are drawn or formed from a single piece or blank of metal. When it is attempted to then form a continuous inturned flange at the upper open end of the generally rectangular or square tub, which may for example have dimensions in a square tub of some 16 or more inches deep, some 27 or more inches across corners, and some 22 or more inches across flats, the difficulties are increased because the inturned flange may decrease the size of the open upper end of the receptacle as much as 3½ inches across corners or across flats. Thus, a large amount of material must be displaced and rearranged in the upper end of the side and rounded corner walls of the generally rectangular or square receptacle, which sheet metal walls, although composed of ductile material, have already been subjected to most severe deep drawing operations in forming the deep generally rectangular or square receptacle from a single metal blank.

Many problems have been involved in making a similar round sheet metal receptacle with a bullet-nose or bottle-neck in which there is an inturned flange at the top edge thereof, as shown in the French et al. Patent No. 2,131,027. However, entirely different problems are encountered when it is attempted to make a generally rectangular or square receptacle with a continuous inturned flange at the top thereof, because of the shape desired.

Moreover, such receptacles when used as tubs for washing machines and formed of sheet steel, are usually covered with a vitreous enamel coating, and it has been believed by some users that a proper, or satisfactory, or uniform vitreous enamel coating could not be applied satisfactorily to a drawn sheet steel article for use as a washing machine tub, unless the article is free of cutting, slitting, seams or welds.

As previously pointed out, it has been believed in the past that it would be impossible to produce a restricted opening, generally rectangular or square sheet metal receptacle free of slitting, cutting, seams or welds, and for these reasons there is no prior art or prior practice known to me indicating how the manufacture of such a receptacle may be accomplished by whatever means employed.

It is therefore a principal object of the present invention to provide a new method of forming a substantially rectangular or square restricted opening receptacle with an integral bottom wall from a single sheet or blank of sheet or plate metal, preferably from sheet steel.

Furthermore, it is an object of the present invention to provide a method of forming a continuous inturned flange free of cutting, slitting, seams or welds at the upper open end of a substantially rectangular or square receptacle having rounded corners, so as to provide a restricted opening for such receptacle.

Likewise, it is an object of the present invention to provide a new, substantially rectangular or square sheet metal receptacle having rounded corners, an integral bottom wall, and an inturned integral flange at the upper open end thereof, all free of slitting, cutting, seams or welds.

Also, it is an object of the present invention to provide a method of forming an upturned or downturned flange or a sinuous or other desired shape in a continuous inturned flange free of cutting, slitting, seams or welds, at the upper open end of a rectangular or square receptacle having rounded corners, so as to provide any de-

sired shape for the restricted opening for such receptacle.

Likewise, it is an object of the present invention to provide a new, substantially rectangular or square sheet metal receptacle having rounded corners, an integral bottom wall, an inturned integral restricted opening flange at the upper open end, and an upturned, downturned, sinusous or other formed shape in said inturned flange, all free of slitting, cutting, seams or welds.

Moreover, it is an object of the present invention to provide a vitreous enamel coated, generally rectangular or square, sheet metal receptacle having integral sheet metal bottom, side and rounded corner walls terminating in an integral inturned or inturned and shaped flange forming a restricted opening therefor, free of slitting, cutting, seams or welds.

Likewise, it is an object of the present invention to provide a method of making a substantially rectangular, or square restricted opening receptacle by cold working, stamping, pressing, drawing, forming, shaping, upsetting, bending, tensioning, stretching, piercing, trimming, and heat treating operations, which may be quickly and readily performed without wasting any substantial amount of material.

And finally, it is an object of the present invention to provide an improved method of making a restricted opening shape in closed bottom receptacles of different sizes and heights deep drawn integrally from single metal blanks, which satisfy the desiderata described above, and which may be carried out in an inexpensive manner with a minimum of operations, cost and waste for producing the improved restricted opening sheet metal receptacles disclosed herein.

The foregoing and other objects are obtained by the steps, methods, procedures, processes and products which comprise the present invention, the nature of which is set forth in the following general statements, preferred embodiments of which are set forth in the following description, and which are particularly and distinctly pointed out and set forth in the appended claims forming part hereof.

The nature of the improved method of the present invention may be stated in general terms as preferably including among others, the steps of forming a closed bottom, generally rectangular or square receptacle with rounded corners from a single blank of sheet or plate metal by a deep drawing operation; annealing the deep drawn shell; stretching the flat sides between, but not the rounded corners of, the deep drawn shell, and re-forming the bottom wall of the receptacle to the desired shape; punching and piercing the bottom and side walls to provide the desired openings and holes therein; trimming off the outwardly projecting flange formed during said deep drawing operation; cold working, pressing, drawing, forming, shaping, upsetting and bending the metal at and adjacent the upper edge of the trimmed shell at each corner thereof to provide a rounded inturned flanged area thereat; locally annealing the shell at and adjacent the top edges and formed inturned corner areas thereof; cold working, pressing, drawing, forming, shaping and bending the metal in the shell at and adjacent the edges above the flat sides thereof and between the formed inturned corner flanged areas to provide inturned flanged areas extending between the inturned corner flanged areas; trimming excess metal from the inner free edge of the continuous in-

turned flange at the upper edge of the flat side and rounded corner walls of the shell; pressing, drawing, forming, bending, shaping and curling the inner free edge of said continuous inturned flange to form a continuous downturned flanged extremity thereat; pressing the shell to square, true and size the same for producing a finished generally rectangular or square restricted opening receptacle, free of cutting, slitting, notching, patching, seams or welds; and then providing a vitreous enamel coating on the surfaces of the receptacle if desired.

The nature of the improved product may be stated in general terms as including an integral, one-piece sheet metal receptacle having a bottom wall, preferably slightly crowned substantially flat side walls with connecting rounded corner walls extending integrally upwardly from said bottom wall to provide a generally rectangular or square shape in cross section, and a continuous inturned flange at the upper ends of said flat side and rounded corner walls forming a restricted opening for said substantially rectangular or square receptacle; said receptacle walls and inturned restricted opening flange being free of slitting, cutting, notching, patching, seams or welds.

By way of example, an embodiment of the improved product in the form of a generally square restricted opening receptacle, and somewhat diagrammatic representations of steps of the improved method, are illustrated in the accompanying drawings forming part hereof, in which

Figure 1 is a top plan view of a substantially square shell with rounded corners drawn by a deep drawing operation from a single sheet metal blank;

Fig. 2 is a section taken on the line 2—2, Fig. 1.

Fig. 3 is a view similar to Fig. 1 illustrating a succeeding operation of stretching the flat side walls, but not the corner walls of the shell, and re-forming the bottom thereof;

Fig. 4 is a section taken on the line 4—4, Fig. 3;

Fig. 4a is a fragmentary plan section of one of the dies used in carrying out the stretching operation illustrated in Fig. 3;

Fig. 4b is a section taken on the line 4b—4b, Fig. 4a;

Fig. 5 is a view similar to Fig. 3 showing a succeeding piercing and punching operation for providing a central opening and bolt holes in the bottom wall of the shell;

Fig. 6 is a view similar to Fig. 4 showing a succeeding trimming operation for removing the outturned flange from the shell shown in Fig. 5;

Fig. 7 is a top plan view of the shell shown in Fig. 6 after one top corner thereof has been re-formed to provide an inturned flanged area thereat;

Fig. 8 is a section taken on the line 8—8, Fig. 7;

Fig. 9 is a view similar to Fig. 7, but showing the inturned flanged areas formed at all four of the top corners of the shell;

Fig. 10 is a view similar to Fig. 9, illustrating a succeeding operation of locally annealing the top and formed corner areas of the shell;

Fig. 11 is a section taken on the line 11—11, Fig. 10;

Fig. 12 is a view similar to Fig. 9, showing a succeeding operation of forming an inturned flanged area at one side between formed corner areas;

Fig. 13 is a view similar to Fig. 12, showing the

inturned flange formations at all sides between formed corner areas;

Fig. 14 is a section taken on the line 14—14, Fig. 13;

Fig. 15 is a view similar to Fig. 13, showing a succeeding operation of trimming excess metal from the inner edge of the continuous inturned flange at one corner portion thereof;

Fig. 16 is a view similar to Fig. 15, showing the completely trimmed inturned flange;

Fig. 17 is a fragmentary section taken on the line 17—17, Fig. 16;

Fig. 18 is a view similar to Fig. 16, showing a succeeding operation of forming or curling the inner edge of the inturned flange to provide a downturned curl thereat in one corner of the blank;

Fig. 19 is a section taken as on the line 19—19, Fig. 18, illustrating a completed downturned curl around the entire inner edge of the inturned flange;

Fig. 20 is a perspective view of the completed, deep drawn, one-piece, substantially square, restricted opening receptacle, free of slits, cuts, patches, notches, seams or welds, which may be provided in a vitreous enamel coating if desired; and

Figs. 21 and 22 are views similar to a part of Fig. 19 showing modified shapes applied to the continuous inturned flange.

Similar numerals refer to similar parts throughout the various figures of the drawings.

A succession of steps by which a rectangular receptacle such as one having a substantially square shape with a restricted opening is formed from a single metal sheet or blank free from seams or welds, is shown in the drawings; but it is to be understood that the method in its broadest aspects is applicable to the formation of various sizes of rectangular restricted opening receptacles having dimensions or relationships of dimensions different from the particular embodiment shown in the drawings. Moreover, the receptacle need not necessarily be used as a washing machine tub, but a restricted opening receptacle formed of one-piece with or without openings or holes in the bottom or sides thereof may be used for any other desired purpose.

In carrying out the improved method, a suitably shaped blank of sheet metal is introduced between suitably shaped draw dies, and subjected therein to a deep drawing operation to form the deep drawn shell 21, illustrated in Fig. 1, which may include a bottom wall suitably rough formed to a desired shape indicated at 22, from which four substantially flat side walls 23 extend upwardly, joined by curved or rounded corner walls 24, which side and corner walls 23—24 terminate in the outturned shell flange 25.

Although the side walls 23 have been described as being substantially flat, it may be preferable to form them with a very slight outward curvature or convexity for preventing the same from developing any buckling or warping tendencies and for holding the desired final shape. This slight curvature or convexity is ordinarily not noticeable to the eye, and the structure may therefore be said to have substantially flat side walls.

Moreover, some substantial curvature may be desired at each of the corners, and the corner walls 24 are therefore rounded corner walls, so that the particular structure shown is properly described as being substantially square in shape. The deep drawn shell 21 is then preferably sub-

jected to a full annealing operation in a suitable heat treating furnace for relieving stretcher strains in the following stretching operation in order to prevent buckling or warping of the substantially flat surfaces.

In the next operation, the side walls 23 of the shell are stretched somewhat to stiffen and properly shape the same, although the corner walls 24 are not stretched during this operation. The operation may be performed in suitably shaped dies 26 fragmentarily illustrated in Figs. 4a and 4b, in which the flange holding pads 27 are relieved at the corner areas 27a, so that the shell flange 25 is not gripped at the corner areas thereof.

However, the dies 26 are suitably shaped by a rib and recess formation 28 and 28a adjacent each receptacle side wall so as to initially form a holding rib 29 in the shell flange 25 for carrying out the operation of stretching the side walls 23. The approximate final desired shape 22a of the bottom wall is preferably formed in the bottom wall during the side stretching operation by suitably shaping the dies so that the bottom is finally formed at the same time as and in conjunction with the stretching of the side walls.

If it is desired to provide any openings such as the central opening 30 (Fig. 5), and bolt hole openings 31 in the bottom wall 22a of the shell 21, and openings in any of the side walls, such as the openings 32 and 33 (see Figs. 17, 19 and 20) for use in mounting the receptacle as a tub for a washing machine, or for any other purpose, such openings and holes may be provided by a piercing and punching operation with suitably shaped and operating dies, following the side stretching operation.

In the next operation, the shell 21 is trimmed to have the shape shown at 21a in Fig. 6, by removing the flange 25. This trimming operation may be performed by any suitable means. A usual form of cooperating trimming rollers has been found to work very satisfactorily.

In the next operation, the upper ends of the side and corner walls 23 and 24 at and adjacent the corners 24 are cold worked, pressed, drawn, formed, shaped, upset and bent between suitably shaped dies to provide a rounded inturned flanged area 34 thereat (see Figs. 7, 8 and 9); and this corner forming operation is preferably accomplished in a suitably shaped die, which operates on one corner at a time in order to avoid the necessity of providing complicated dies for forming all four corner areas 34 at one time.

When the corner flanged areas 34 are formed, they are preferably shaped so as to provide a rounded connection 35 (see Fig. 8) between the side and rounded corner walls 23, 24, and the inturned substantially flat flange portion 36 of the corner areas 34. The metal working operation by which the corner areas 34 are formed, results in producing a characteristic inner free edge of the formed metal comprising scallops 37 adjacent the corners, and flaps 38 adjacent the side walls due to the severe drawing, forming, shaping, bending, stretching and rearrangement of the metal during the operation.

After this corner forming operation has been performed on all four corners, the shell has the appearance of the shell 21b illustrated in Figs. 9, 10 and 11.

Because of the severity of the operation of forming the flanged areas 34, it is preferable to locally anneal the upper ends of the side and corner walls 23 and 24 of the shell 21b, the flanged

areas 34, and the scallops 37 and flaps 38, and this may be accomplished by rotating the shell 21b while directing torches 39 and 40 against said areas, as shown in Figs. 10 and 11.

In the next operation, the formation of the in-turned flange at the top of the side walls 23 is completed by cold working, pressing, drawing, forming, shaping, and bending the metal of the shell 21b and particularly the flap portions 38 between the formed flange corner areas 34 thereof between suitable dies which results in a formed shape such as shown in Figs. 12, 13 and 14.

This forming operation is likewise preferably performed in four steps to simplify die construction, so that one side flanged area 41 (Fig. 12) is produced at a time at the upper end of one side wall 23. When all four side flanged areas 41 have been formed, the shell has the shape of the shell 21c shown in Figs. 13 and 14, in which a substantially flat in-turned flange 42 runs continuously around the upper end of the receptacle joined by a small curved or rounded portion 35 to the side and corner walls 23 and 24. The inner free edge of the flange 42 may still have a characteristic remaining scallop formation 37a adjacent each corner.

The operations of forming the corner flanged areas 34 and the side flanged areas 41 must be carefully carried out because of the severity of the operations in substantially restricting or reducing the size of the opening, or, in other words, in necking-in the upper end of the shell, and in bending and rearranging and curving and flattening the metal, which metal has been severely worked in the initial deep drawing operation. For these reasons, the dies which perform the step shown for instance in Fig. 7, work on the metal substantially from the center line of one side wall to the center line of the side wall around the corner being formed; and the dies which perform the operation illustrated for instance in Fig. 12, work on the metal from one scallop formation 37 at one corner to the scallop formation 37 at the adjacent corner.

Thus, substantially all of the metal in the resulting continuous in-turned flange 42 is subjected to two die operations before the continuous in-turned shape is produced. Moreover, any irregularities due to gathering or slight excess of metal accumulates adjacent the corners at the characteristic scallops 37a.

In the next operation, the shell 21c is trimmed to properly size the in-turned flange 42 and remove the scallops 37a; and this is preferably accomplished by suitable trimming dies operating on one corner of the flange 42 at a time, as shown in Fig. 15. After this flange trimming operation has been performed, the shell has the shape of the trimmed shell illustrated at 21d in Figs. 16 and 17.

The shell 21d could be sized and finished at this time, but in many instances it is desired that the continuous in-turned flange 42 have a somewhat curled shape by terminating in a downturned flange, and this may be accomplished by pressing, drawing, forming, bending, shaping and curling the inner free edge of the continuous in-turned flange 42 by suitably shaped dies to form the continuous curled downturned flanged extremity 43 (Fig. 19) at the inner edge of the flange 42. Again, for the purpose of simplifying die construction, this operation may be performed in four steps by working on one corner at a time, as illustrated in Fig. 18, and when completed,

the shell has the shape of the semi-finished receptacle 21e illustrated in Fig. 19.

The shell 21e is then pressed in suitably shaped dies to square, true and size the same for producing the finished generally square restricted opening receptacle 44, illustrated in Fig. 20, which is free of cutting, slitting, notching, patching, seams, or welds in all of the metal walls thereof.

If it is desired that the sheet metal receptacle 44 have a vitreous enamel coating thereon, the same may then be applied thereto in the usual manner.

The one-piece sheet metal receptacle product 44, illustrated in Fig. 20, has a bottom wall 22a, which may have any desired form or shape, from which preferably substantially flat side walls 23 with connecting rounded corner walls 24 extend integrally upward. The side and corner walls 23 and 24 terminate in a continuous integral in-turned flange 42 at their upper ends, which may be further formed in any desired shape, forming a substantially square restricted opening receptacle free of slitting, cutting, notching, patching, seams, or welds.

Although in the particular embodiment shown, the in-turned flange 42 is further formed to provide a downturned curl 43 at its inner extremity, any desired formation may be made in the in-turned flange 42 as the upturned rounded bead 43a shown in Fig. 21 or the sinuous curved formation 43b shown in Fig. 22, or the same may be angularly bent at one or more places to any degree in either direction. Moreover the particular curvature shown at 35 is not the only shape that can be formed. Likewise the in-turned flange 42 may be made without further formation or may be angled upward or downward.

Various forms of restricted openings are known in the art as "bullet-nose," or "bottle-neck," or "inverted bottle-neck" or "turtle-neck" shapes; and the present invention is not limited to the formation of any particular or specific shape of the restricted opening at the top of a rectangular receptacle but is applicable to all forms of restricted openings.

Likewise, although a generally square receptacle is shown and specifically described, the present invention is not limited to the manufacture of a "square" receptacle but is equally applicable to the manufacture of a rectangular receptacle or a multi-sided receptacle such as a three-sided, or a five-sided, six-sided, etc., receptacle. Therefore, the term "rectangular" used herein and in the claims, comprehends such shapes.

It is not intended to limit the scope of the present invention to the particular substantially square restricted opening receptacle shown, because it is clear that other rectangular or multi-angular restricted opening shapes may be made in accordance with the improved method by utilizing dies having the desired shape. Nor is it intended to limit the scope of the present invention to a method of making receptacles used solely as tubs for washing machines, because it is clear that other vessels or containers having a square, rectangular or multi-angular shape and a restricted opening may be made in accordance with the improved method.

Moreover, the term "sheet metal" used herein and in the appended claims, is intended to refer to sheet or strip or plate metal of the desired composition and ductility.

Likewise, in stating that the resulting product is free of slitting, cutting or notching, it is

not meant that the edges of the metal are not slit or cut as by the trimming operations illustrated in Figs. 6 and 15, or that necessary holes are not formed therein as by the punching and piercing operation illustrated in Fig. 5; but that no slits, cuts, seams or welds are present in the metal of the finished metal walls.

Moreover, it is not intended to limit the invention to the exact sequence of steps set forth in order that the method may be satisfactorily performed, because obviously certain of the steps may be combined, or rearranged in a different order, although in some instances it is necessary that certain of the steps follow in the sequence described.

For instance, the combined punching and piercing step illustrated in Fig. 4 might in certain instances be separated. By using more complicated dies, certain of the four step corner flange forming operations of Fig. 7 might be combined in one or more operations. Likewise, the local annealing step of Fig. 10 may be repeated at a subsequent time or at a prior time, although it is probably necessary to perform the same sometime during the operations of forming the continuous inturned flange 42.

Moreover, it is not intended to limit the present invention to the manufacture of a receptacle which is enamel coated, or which is not enamel coated; since the enamel coating may be provided if desired, and if it is provided, the character of the formed receptacle is such that the enamel coating may be readily applied.

Finally, in the foregoing description, certain terms have been used for brevity, clearness and understanding; but no unnecessary limitations are to be implied therefrom beyond the requirements of the prior art, because such words are utilized for descriptive purposes herein and not for the purposes of limitations, and are intended to be broadly construed.

Accordingly, the improved method provides not only an inexpensive way, but in so far as I am informed, the first and only way that has ever been utilized for making a rectangular restricted opening receptacle without wasting material, from a single blank of sheet metal, free of cutting, slitting, notching, patching, seams or welds; and accomplishes the objectives previously set forth herein.

I claim:

1. The method of making a rectangular restricted opening receptacle which includes the steps of drawing a substantially rectangular shell from a sheet metal blank to form a bottom wall terminating in upwardly extending substantially flat side and connecting rounded corner walls; then vertically stretching the substantially flat side but not the rounded corner walls; and then forming a continuous inturned flange at the upper edge of said side and corner walls by working the metal at and adjacent said upper edge between dies without notching, patching, seaming, or welding said metal.

2. The method of making a rectangular restricted opening receptacle which includes the steps of drawing a substantially rectangular shell from a sheet metal blank to form a bottom wall from which substantially flat side and connecting rounded corner walls extend upward and terminate in an outturned flange; gripping said outturned flange adjacent the substantially flat side but not the rounded corner walls, and pressing the bottom wall downward to stretch said side walls; trimming off said outturned flange; and

then forming a continuous inturned flange at the upper edge of said side and corner walls by working the metal at and adjacent said upper edge between dies without notching, patching, seaming, or welding said metal.

3. The method of making a rectangular restricted opening receptacle which includes the steps of drawing a substantially rectangular shell from a single sheet metal blank to form a bottom wall terminating in upwardly extending substantially flat side and connecting rounded corner walls; then forming a continuous inturned flange at the upper edge of said side and corner walls without notching, patching, seaming, or welding the metal in said walls by working the metal between dies in areas at the upper ends of the side and corner walls at and adjacent to the connecting rounded corners to form inturned corner flanged areas thereat, and by reworking portions of the corner flanged areas and working the metal between dies in the areas at the upper ends of the side walls; and then pressing the formed shell to square, size and true the same.

4. The method of making a rectangular restricted opening receptacle comprising the steps of deep drawing a substantially rectangular shell from a sheet metal blank to form a bottom wall terminating in upwardly extending substantially flat side and connecting rounded corner walls; annealing the deep drawn shell; stretching the flat sides between, but not the rounded corners of, the deep drawn shell, and re-forming the bottom wall of the shell to the desired shape; punching and piercing the walls to provide the desired openings and holes therein; trimming off the outwardly projecting flange formed during said deep drawing operation; working the metal at and adjacent the upper edge of the trimmed shell at each corner to provide an inturned flanged area thereat; locally annealing the shell at and adjacent the upper edges and formed inturned corner areas thereof; working the metal at and adjacent the edges above the flat sides thereof and between the formed inturned corner flanged areas to provide inturned flanged areas extending between the inturned corner flanged areas; trimming excess metal from the inner free edge of the continuous inturned flange; and pressing the blank to square, true and size the same to produce a receptacle free of cutting, slitting, notching, patching, seams or welds.

5. The method of making a rectangular restricted opening receptacle comprising the steps of deep drawing a substantially rectangular shell from a sheet metal blank to form a bottom wall terminating in upwardly extending substantially flat side and connecting rounded corner walls; annealing the deep drawn shell; stretching the flat sides between, but not the rounded corners of, the deep drawn shell, and re-forming the bottom wall of the shell to the desired shape; punching and piercing the walls to provide the desired openings and holes therein; trimming off the outwardly projecting flange formed during said deep drawing operation; working the metal at and adjacent the upper edge of the trimmed shell at each corner to provide an inturned flanged area thereat; locally annealing the shell at and adjacent the upper edges and formed inturned corner areas thereof; working the metal at and adjacent the edges above the flat sides thereof and between the formed inturned corner flanged areas to provide inturned flanged areas extending between the inturned corner flanged areas; trimming excess metal from the inner free edge of the con-

tinuous inturned flange; working the metal in the continuous inturned flange to change the shape thereof; and pressing the blank to square, true and size the same to produce a receptacle free of cutting, slitting, notching, patching, seams or welds.

6. In a method of making a relatively deep, rectangular, restricted opening receptacle from a single sheet metal blank; the steps of deep drawing said blank to form a substantially rectangular relatively deep receptacle shell having a bottom wall terminating in integral upwardly extending substantially flat side and connecting rounded corner walls; and thereafter displacing and rearranging the metal areas in the upper ends of the side and corner walls of said shell without notching, patching, seaming or welding said metal to form an inturned flange of substantial width running continuously around the upper end of the receptacle by cold working, pressing, drawing, forming, shaping, upsetting, stretching and bending the metal between dies in areas at the upper ends of the side and corner walls at and adjacent to said connecting rounded corners to form inturned corner flanged areas thereof, and by reworking portions of the worked inturned corner flanged areas and working, pressing, drawing, forming, shaping and bending the metal between dies in areas at the upper ends of the side walls to complete the formation of said continuous inturned flange.

7. In a method of making a relatively deep, rectangular, restricted opening receptacle from a single sheet metal blank; the steps of deep drawing said blank to form a substantially rectangular relatively deep receptacle shell having a bottom wall terminating in integral upwardly extending substantially flat side and connecting rounded corner walls; and thereafter displacing and rearranging the metal areas in the upper ends of the side and corner walls of said shell without notching, patching, seaming or welding said metal to form an inturned flange of sub-

stantial width running continuously around the upper end of the receptacle by cold working, pressing, drawing, forming, shaping, upsetting, stretching and bending the metal between dies in areas at the upper ends of the side and corner walls at and adjacent to said connecting rounded corners to form inturned corner flanged areas thereof, and by reworking portions of the worked inturned corner flanged areas and working, pressing, drawing, forming, shaping and bending the metal between dies in areas at the upper ends of the side walls to complete the formation of said continuous inturned flange; and then working the metal in the continuous inturned flange to change the shape thereof.

8. In a method of making a relatively deep, rectangular, restricted opening receptacle from a single sheet metal blank; the steps of deep drawing said blank to form a substantially rectangular relatively deep receptacle shell having a bottom wall terminating in integral upwardly extending substantially flat side and connecting rounded corner walls; and thereafter displacing and rearranging the metal areas in the upper ends of the side and corner walls of said shell without notching, patching, seaming or welding said metal to form an inturned flange of substantial width running continuously around the upper end of the receptacle by cold working, pressing, drawing, forming, shaping, upsetting, stretching and bending the metal between dies in areas at the upper ends of the side and corner walls at and adjacent to said connecting rounded corners to form inturned corner flanged areas thereof, and by reworking portions of the worked inturned corner flanged areas and working, pressing, drawing, forming, shaping and bending the metal between dies in areas at the upper ends of the side walls to complete the formation of said continuous inturned flange; and then applying a vitreous enamel coating on the surfaces of the receptacle.

JOHN H. GONDA.
